UNITED STATES PATENT OFFICE.

RALPH S. MEGATHLIN, OF WEST SOMERVILLE, AND ALBERT E. HUDSON, OF BEVERLY, MASSACHUSETTS, ASSIGNEES TO UNITED SHOE MACHINERY CORPORATION, OF PATERSON, NEW JERSEY, A CORPORATION OF NEW JERSEY.

MACHINE FOR OPERATING UPON SHOE PARTS.

Application filed January 12, 1920. Serial No. 350,771.

To all whom it may concern:

Be it known that we, RALPH S. MEGATHLIN and ALBERT E. HUDSON, citizens of the United States, residing at West Somerville, in the county of Middlesex and Commonwealth of Massachusetts, and Beverly, in the county of Essex and Commonwealth of Massachusetts, respectively, have invented certain Improvements in Machines for 10 Operating Upon Shoe Parts, of which the following description, in connection with the accompanying drawings, is a specification, like reference characters on the drawings indicating like parts in the several 15 figures.

This invention relates to machines for handling and operating upon blanks such as shoe parts. The invention is herein illustrated as embodied in a machine for treating 20 toplifts which are to be used for boot and shoe heels.

In the preparation of such articles as leather toplifts for use in the manufacture of boots and shoes, the blanks, after being 25 died out from a sheet of leather, are subjected to a number of treatments especially when they are to be used in making high-grade articles of footwear. To facilitate the making of the shoes and produce the 30 best results these treatments are such as to furnish to the shoemaker a desired number of toplifts which have been subjected to pressure to render them as nearly as possible uniform as to density and thickness, each 35 usually having one surface stamped to indicate the size and commonly having a uniformly even flesh side produced by skiving. In practice it is customary to supply the toplifts to a dealer or shoe manufacturer in 40 definite quantities graded as to sizes.

The principal object of the present invention is to provide an automatic machine capable of taking articles such as toplift blanks as they come from the cutting die, 45 regardless of thickness, density, or other characteristics, and delivering them graded as to thickness size, all having equal density, and each bearing an indication of its size and having an even flesh surface and a 50 polished grain surface, the machine being, however, capable of omitting any of the treatments mentioned.

With this object in view, the illustrated machine comprises an intermittently movable carrier for a series of blanks, means 55 for actuating the carrier to locate the blanks successively at different stations, and means for simultaneously compressing, measuring, ironing and stamping a plurality of blanks, occupying different stations, means being also provided for skiving the blanks and delivering them in graded lots. Since some of these operations may be omitted, however, the invention is not limited to a machine including all of the 60 mechanisms for performing said operations.

Owing to the variations in thickness of different portions of a hide, articles such as soles and heel lifts cut therefrom are not all 65 of the same thickness and frequently individual articles are thicker in some portions of their areas than others. Moreover, the flesh side of the leather is rough and therefore it is customary to skive the flesh side 70 to even and smooth that surface. The expense of leather is such that it is highly desirable to remove a skiving of no greater thickness than is necessary to leave a smooth and even surface.

Accordingly another object of the present 75 invention is to provide a novel mechanism which will remove skivings of predetermined minimum thickness from the flesh side of each of a succession of leather articles regardless of variations in the thickness of different articles. With this object in view, another important feature of the 80 invention comprises a skiving knife, a carrier movable past the knife and having a movable article-supporting member, and means for positioning said member in the carrier according to the thickness of the article. Preferably, and in accordance with another feature of our invention, the machine 85 comprises an endless series of carriers which successively move past the knife, such series of carriers being, in the particular embodiment illustrated, parts of an intermittently rotatable turret.

It is desirable that the thickness sizes of 90 such articles as toplifts shall be indicated on the surfaces thereof. To provide satisfactory mechanism for doing this automatically is another object of the invention, and

to this end another important feature of the invention consists in a marker and means controlled by the positions of the article-supporting members in the carriers for setting and holding the marker until the proper indication of the thickness of each article is applied to that article.

Practically the machine as exemplified herein measures the thickness of each article 10 deposited in a carrier, such measurement being determined by the position to which the article-support is shifted by the depositing operation.

Another object of the invention is to provide improved mechanism for increasing the density of the blanks without impairing the quality of the leather by disintegration of its fibers. In this aspect the invention comprises means for imparting a succession 20 of cumulative pressures to each blank while the latter occupies different stations of the machine successively.

Other objects and novel characteristics of the invention will now be described in connection with the accompanying drawings, and the various features of the invention will then be pointed out in the appended 25 claims.

In the drawings, 30 Fig. 1 is an elevation, partly in section looking from the feed or supply end of the machine;

Fig. 2 is an elevation partly broken out looking from the right of Fig. 1;

Fig. 3 is a plan view partly in section;

Fig. 4 represents a section on line 4—4 of Fig. 2;

Fig. 5 represents a section on line 5—5 of Fig. 2, the same line of section being indicated in Fig. 6;

Fig. 6 represents a section on line 6—6 of Fig. 3 on a larger scale;

Fig. 7 represents a section on line 7—7 of Fig. 3 on a larger scale;

Figs. 8 and 9 are detail sectional views illustrating slightly different structures of one of the compressing plungers;

Fig. 10 represents a detail section on line 10—10 of Fig. 6;

Figs. 11, 12 and 13 are detail sectional views illustrating different steps of the operation of the sliding feed plate;

Fig. 14 represents a detail section on line 14—14 of Fig. 3;

Fig. 15 is a detail sectional view on line 15—15 of Fig. 7, looking in the direction of the arrows; and

Fig. 16 is a detail sectional view, on a scale approximating full size, illustrating the inclined or beveled edges of the openings in the feed slide and one of the mold plates 127, the toplift to be acted upon being omitted.

The detailed description will be more

readily understood by a preliminary explanation that in the use of the machine exemplified in the accompanying drawings, toplifts in the hopper 111 (Fig. 2) gravitate singly into an opening in a slide 113 (Figs. 11, 12 and 13) and by said slide are carried to position or station A (Figs. 2, 3 and 6) where a plunger 143 pushes each toplift into an opening in one of four mold plates 127 all four of which are carried by an intermittently rotated turret having duplicate toplift supporting mechanisms. After a toplift is pushed from the feed slide 113 into a mold plate 127 a further inward movement of the slide 113 shifts said mold plate toward the center of the turret so that the toplift occupies position or station B (Figs. 2 3, 6 and 13). As the turret revolves step by step the toplifts carried by the four mold plates 127 successively occupy positions or stations C, D and E (Figs. 2, 3, 5, 6 and 7) in each of which positions certain operations hereinafter explained are performed on the toplifts. While in station E the toplift is discharged from the mold plate which latter is drawn out to the position indicated by dotted lines in Fig. 7 so that when the turret again moves, that mold plate will remain slid partly out to receive another toplift from the hopper 111 (Fig. 2).

A suitable frame base 20 (Figs. 1, 2, 6 and 7) is formed or provided at its top with a circular track 21, said base having a central sleeve bearing 22. Mounted to rotate intermittently on the base 20 is a turret having a lower ring 23 and a top plate 24 connected by webs 25. Between the ring 23 and the circular track 21 of the base are antifriction bearings consisting of a series of radially arranged rolls 26 the trunnions of which are mounted in an inner cage ring 27 and an outer cage ring 28.

Depending from the top plate 24 is a central tube 29 the lower tubular end of which 30 is rotatively mounted in the sleeve bearing 22 of the base (Figs. 6 and 7). Keyed to the lower end of the hollow vertical shaft 30 is a ratchet ring 31 which, in practice, will have as many notches to be engaged by the pawl presently described, as the turret is to have steps of rotation. The present machine is so designed that the turret has four steps of rotation and therefore the ratchet ring 31 has four notches. Rotatively mounted on the tubular bearing 22 between the lower end thereof and the ratchet ring 31 is a bevel pinion 32 in which is mounted a vertically movable, spring-pressed pawl 33. The pinion 32 is engaged so as to be rotatively oscillated by a toothed segment 34 indicated by dotted lines in Fig. 2, the arm 35 of said segment being pivotally mounted on a stud 36 (Figs. 1 and 2). A short arm 37 of the arm 35 has a roll 38 which engages

a path cam in the disk 39 carried by shaft 40 (Fig. 4). Said path cam actuates the segment 34 and pinion 32 back and forth and the pawl 33 successively engages the notches 5 in ring 31 to give the turret a succession of quarter turns. Shaft 40 is provided with a gear 41 (Figs. 1, 2 and 4) meshing with a pinion 42 carried by a stud shaft 43 having a gear 44, the latter meshing with a pinion 45 on the driving shaft 46 having fast and loose pulleys 47.

Rising from the base 20 are three frame brackets 48 (Figs. 1, 2 and 3) to the upper ends of which is rigidly secured a crown plate 49. Vertically movable relatively to the crown plate and frame is a head 50 carrying a series of plungers, presently described. Said head 50 is formed or provided with vertically elongated lugs 51 each having a vertical aperture in which is mounted a rod 52, each of the rods 52 being secured in one of the lugs 51 by suitable means such as a binding screw illustrated in Fig. 2, the ends of the rods 52 projecting 20 above and below the lugs 51 into apertures in bearing lugs 53 of the brackets 48. In other words, the three rods 52 and their bearings 53 provide for vertically guiding the head 50.

Depending from the head 50 are three plungers 54, 55 and 56, relatively positioned to act simultaneously on toplifts in stations B, C and D. These three plungers are substantially alike, with an exception herein-after explained, but they are indicated in the drawings by different numerals because certain operations are effected by said plungers in the order in which they are numbered. Each plunger is vertically adjustable relatively to the head 50 as by means of a screw-threaded portion 57 (Fig. 2) engaging a clamping tubular bracket portion of the head 50.

To reciprocate the head 50 and its plungers vertically at the proper times while the intermittently rotatable turret is stationary, a rod 58 (Fig. 7) depending from the center of the head and passing through the central tube 29 of the top plate of the turret and 50 through the hollow shaft 30, is connected at its lower end to a lever 59 indicated by dotted lines in Fig. 2, said lever being pivotally mounted at 60 and having its other end connected by a link 61 to an arm 62 of an elbow lever, said lever being pivoted at 63 and having its other arm 64 provided with a roll 65 entering a path cam in the disk 66 (Fig. 4) carried by shaft 40.

The cam for actuating this mechanism, 60 like the other cams carried by the shaft 40, is a quadruple operating cam, because, as will be more fully explained hereinafter, the head 50 and its plungers operate four times during each rotation of the shaft 40, each 65 movement of the plunger head simultane-

ously effecting four different operations upon four toplifts which are at stations B, C, D and E, respectively. The intermittently rotatable turret hereinbefore referred to is provided with four chambers or pockets 67, two of which are shown in Fig. 6 in sectional detail and the other two in Fig. 7 in similar sectional detail, these two views being sections at right angles to one another. In the bottom of each chamber or pocket is an externally threaded bushing 68 which is internally smooth to form a bearing for the tubular stem 69 (Fig. 6) of a piston-like support or table 70. A spring 71 bearing on the upper end of the bushing 68 normally holds the support or table 70 at an elevation in the chamber 67 determined by a double-flange collar 72 having a screw-threaded connection with the lower end of the tubular stem 69. Therefore, by adjusting the bushing 68 vertically in the bottom of the chamber 67, the compression of the spring 71 may be varied to afford more or less resistance to the downward pressure of toplifts which is effected as herein-after described. The under surface of the upper flange of the collar 72 bears on a strip 73 (Figs. 5 and 6) which bridges the space between the arms of a forked lever 74 one end of which is pivotally supported at 75 by lugs depending from the pocket or chamber. At an intermediate point the lever 74 is provided with a roll 76 which extends under a stationary ring 77 supported by a flanged portion of the sleeve bearing 22 which rises above the plane of the lower turret ring 23, as indicated in Figs. 6 and 7. The purpose of the ring 77 will be explained hereinafter.

The inner end of each fork lever 74 has a pawl 78 pivotally connected to it and actuated by a spring 79 (Fig. 7) into engagement with a vertical ratchet strip 80 attached to the central tube 29 of the turret. At one point or station at each step of rotation of the turret, the pawl 78 is released or unlocked from its ratchet 80. For convenience of description this point or station is indicated at C and is the position shown at the left in Fig. 7. The other stations temporarily occupied by each of the chambers or pockets of the turret are indicated respectively at B, D and E in Figs. 6 and 7, and the operation effected upon a toplift at each of said stations will be described hereinafter.

In order to release or unlock the pawl 78 from the ratchet 80 when a pocket and a lever 74 have passed from station B to station C, we provide an angle lever 81 (Fig. 7) pivotally supported at 82 in proper location by the frame base to act upon the pawl 78 when station C is reached. At this point the lower end of the pawl 78 has arrived opposite the upper end of the angle 125 130

lever 81, the tip 83 of the lower arm being engaged for actuation by means presently described. Before describing the means for tripping the pawl 78 through the medium 5 of the angle lever 81, it is advisable to explain that said pawl 78 is again unlocked from the ratchet 80 when station D is reached (Fig. 6). To this end, an angle lever 84, similar to the angle lever 81 is pivotally supported at 85 and its lower arm 10 has a tip 86.

In order that the pawls 78 of the levers 74 may be simultaneously released at the proper times when in stations C and D, the 15 vertically movable plunger operating rod 58 is provided with a fixed collar 87 (Figs. 6 and 7) having lugs provided with pivots 88 for fingers 89. Springs 90 tend to press the lower ends of fingers 89 outwardly so 20 that, each time when the center rod 58 moves downwardly, the lower ends of the fingers will pass through openings 91 in the central tube 29 of the turret and act on the tips 83, 86, of the levers 81, 84, to cause the other 25 ends of said levers to release the two pawls 78 then in stations C, D. Mounted in each tubular stem 69 (Figs. 5 and 6) is a shaft 92 having a clutch member 93 at its lower end and at its upper end having an eccentric 30 stud 94 loosely entering a central socket in a disk or circular block 95 which will be hereinafter referred to as the "iron" because its function is to iron the under surface of a toplift pressed thereagainst by 35 one of the plungers as hereinafter described. Depending from the turret top plate 24, between each pocket 67 and the central tube 29, is a sleeve 96 preferably having a screw-threaded connection between its upper end 40 and the plate 24 to enable said sleeve to be set in vertical adjusted position. Mounted in this sleeve is a slide 97 (Fig. 6) having a lower reduced end or shank 98 mounted in an opening in the bottom of the sleeve bearing 96 and having pivotally connected to its lower end a vertically slotted link 99 (Fig. 7) a pin 100 of the lever 74 entering said slot. Secured to the shank 98 is a block having a tooth 101 to coact with a 45 ratchet detent 102 pivoted at its upper end 103 to a collar 104 secured to the sleeve 96. A suitably connected spring 105 exerts a normal tendency to hold the lower end of the detent 102 in contact with a ring-shaped 50 member at the top of the base frame, said ring-shaped member having a cam rise 106 (Figs. 5 and 6) located in the proper position to swing the detent 102 outwardly to disengage its ratchet teeth from the tooth 101 when station B is reached. As soon 55 as the slide 97 is free from the detent 102, it is forced upwardly by a spring 107 around the stem 98 within the sleeve 96.

60 Mounted in a recess in slide 97 is a pivoted ratchet 108, a spring 109 being located

70 to hold said ratchet 108 normally in the position shown at the left in Fig. 6 and out of contact with a fixed locking tooth 110, the object or purpose of which will be explained hereinafter.

To supply toplifts for operation between the plungers and the members carried by the turret we employ any suitable hopper 111 indicated in Fig. 2, supported by bracket 112 rising from the base 20. The bottom of the hopper consists of a slide 113 having an opening 114 (Figs. 3 and 11) into which the lower toplift in the hopper will drop when said opening is in alinement with the bottom of the hopper. Preferably the opening 114 is of a size and shape approximating that of the toplifts in the hopper and the edges of said openings are preferably slightly tapering downwardly so that a toplift, when it first drops into the opening, will 80 be engaged therein sufficiently to be carried readily by the slide, the lower portion of the opening being slightly smaller than the toplift so that, when the toplift is pushed down through the opening 114 into another 85 slide member 127 below it, to be presently described, the toplift will be slightly contracted by the walls of the opening 114 and guided thereby into the opening of said other slide 127.

To actuate the slide 113 so that it will 90 act to feed a toplift to station A in Figs. 2 and 3, a pair of links 115 suitably connect said slide with the bifurcated upper end of a lever 116 pivoted at 117 to a bracket 118 of the frame base. The short arm of said lever is connected by a link 119 (Figs. 2 and 4) to an arm 120 of a hub 121 mounted on a pivot shaft 122. Arm 123 of said hub has a roll engaged by a path cam in a disk 124 secured to the shaft 40. The upper surface of the bracket 112 has a longitudinal groove 125 (Fig. 3) into which a block 126 extends from the under side of the feed slide 113 (see also Fig. 2). The object of the block 126 is to engage the outer end of each mold plate 127 when one of said plates is in the position shown in Fig. 3. There are four of the mold plates 127 each being mounted to slide laterally on the turret, guided in ways 128 secured to the top plate 24 of the turret. Each mold plate has a toplift-shaped opening 129 which, in practice, is so formed that its walls will laterally contract or condense a toplift 110 forced thereinto, as hereinafter described.

The cam which actuates the levers 120, 115 116 so as to shift the slide 113 inward, is a two point cam unnecessary to illustrate or describe in detail, said cam being formed and provided to first move the slide 113 from the position which it occupies to receive a toplift from the hopper 111 (Fig. 11) to a position where its opening will be 120 in alinement with the opening of slide 127 125 130

(Fig. 12). The next step of the cam acts to move the slide 113 in so that its block or lug 126 will push the mold plate 127 in until the openings of the slide and mold plate 5 are between and in alignment with the plunger 54 (Figs. 2 and 6) and the pocket 67 which is then under plunger 54. There is sufficient dwell of the action of the two portions of the feed cam to permit the complete 10 transfer of the toplift from the feed slide to the mold plate before the latter is shifted to station B. The mechanism for doing this is located in a portion of the machine which we refer to as station A.

15 Referring to Fig. 6 in connection with Fig. 2 a chamber or pocket 130 supported by a bracket portion of the frame has fitted within it a piston-like support or table 131, its stem 132 extending through a bearing or 20 guide opening in the bottom of the pocket. Removably and changeably fitted to the upper face of the support or table 131, as by dowels is a facing plate 134 whereby provision may be made for operation upon 25 toplifts of varying widths, by employing a facing plate of required size. Fig. 10 indicates a sectional view of the upper portion of the pocket 130 at a right angle to the line of section in Fig. 6. Inasmuch as the 30 mold plate is necessarily thin, it is desirable that it shall not be buckled downwardly when a toplift is forced into its opening by the plunger 143, hereinafter described. To effect this support of the mold plate 127 we 35 provide the upper end of the pocket 130 with a pair of parallel strips 135 (Fig. 10) having a thickness sufficient to prevent downward bending or distortion of the mold plate. Similar strips 135 may be employed 40 in connection with the pockets 67 of the turret.

The lower end of the stem 132 of the support or table 131 is connected with a lever 136 (Fig. 2) pivotally supported at 137, the 45 outer end of which has a dog 138 pivotally connected to it, the tooth of said dog engaging a frame-supported ratchet 139 the teeth of which are shaped to prevent upward movement of lever 136 under the influence 50 of spring 133 so long as the toothed member 138 engages said ratchet. To disengage or unlock the toothed member 138 from the ratchet 139 at the proper time, a tripping lever 140, pivotally connected to the frame 55 bracket, has one end adapted to contact with the inner face of the lower end of the pivoted dog 138, the other end of the lever extending outwardly under a roll or pin 142 of the lever 116. The shape of the 60 tripping lever 140 is such that its outer end is depressed by the pin 142 when the lever 116 moves outwardly so that the inner end of said tripping lever will act on the dog 138 to unlock its tooth from the ratchet. 65 When a toplift has been shifted by the

feed plate 113 to station A where the opening 114 is in alignment with the opening 129 of an underlying mold plate, said toplift is forced down and located in said opening 129 by a plunger 143 (Figs. 1, 2 and 6). 70 Preferably, and as indicated in Fig. 1 partly by dotted lines, the plunger 143 has two stems 144 mounted in guides at opposite sides of two brackets 145 which are suitably supported by a lower frame bracket of the 75 base frame 20. Supported by said brackets 145 is a rock shaft 146, the middle portion of which carries the upper member of a toggle 147, the lower member of which is connected to the plunger, as shown by comparing Figs. 1 and 2. Connected to the ends of rock shaft 146 are two arms 148 which are connected by links 149 with a bar 150 carried by the outer end of a lever 151 pivotally mounted on shaft 122 and having its inner end provided with a roll acted upon by a path cam in a disk 152 (Fig. 4) carried by shaft 140. The timing of operation of this cam is such as to cause the plunger 143 to transfer a toplift from feed plate 113 80 into a mold plate when the latter is in station A of Figs. 2 and 3, thereby partly compressing the toplift and locating it in the opening of the mold plate ready for the latter to be transferred by means of the lug or block 126 of slide 113 from said station A in and completely along the ways 128 until the opening of the mold plate is under plunger 54 for operation in station B. The 85 compressing operation at stations B and C 90 will be described hereinafter.

As hereinbefore mentioned, the plungers 54, 55, 56 are vertically adjustable relatively to the head 50 which always descends to a predetermined plane. This is to adapt the machine to properly compress, mold and iron blanks of different thicknesses or qualities of leather. And for the best results it is essential that they shall be independently adjustable. The structure illustrated provides for such independent adjustment. It is also desirable that the plunger 143 which operates at station A shall be adjustable so that upon its down stroke its lower surface will pass more or less below the plane of the 105 bottom of the feed slide 113. Any suitable means for effecting this adjustment may be provided, such as right-and-left turn-buckles in the links 149 whereby said links may be 110 lengthened or shortened. 120

As the turret is rotated, and while it is being moved from station C to station D (Fig. 3), the flesh or upper side of the toplift in opening 129 is skived by means of a knife 153 shown by comparing Figs. 3 and 6. Said knife is carried by a holder 154 which is vertically adjustable (Figs. 1 and 14). To effect this vertical adjustment the holder 154 has a recess or socket fitting the 125 reduced upper end or bearing 155 of a 130

bracket 156 rising from the frame base 20. A screw 157 having a handle 158 is rotatively mounted in the top of the recessed portion of holder 154 and enters the top of the bearing 155. By means of the handle 158 the screw is rotated to vertically adjust the plane of operation of the edge of knife 153 so as to skive more or less of the toplifts, or according to the thickness of the toplifts being operated upon. The knife has a shearing action across the top of each toplift as the latter moves with the turret from station C to station D, the longitudinal shape of said knife being indicated by dotted lines 15 in Fig. 3.

The lower face of each toplift is ironed when it reaches station D. That station is indicated at the right of Fig. 6 where it will be seen that the clutch member 93 at the 20 lower end of the shaft 92 is in clutching engagement with a clutch member 159 which at this point has been raised to intermesh with member 93. Said lower clutch member 159 is carried at the upper end of a vertical 25 shaft 160 rotatably mounted in a bearing 161 extending in from the wall of the frame base 20. At the lower end of shaft 160 is a bevel gear 162, indicated by dotted lines in Fig. 2 and partially broken away in Fig. 4. 30 Said gear meshes with a bevel gear 163 carried by the driving shaft 46. The relative sizes of the intermediate gears between shafts 46 and 40 are such as to very materially reduce the speed of rotation of shaft 35 40 relatively to that of shaft 46. In other words shaft 46 revolves very rapidly as compared with shaft 40. Therefore, the vertical shaft 160 is constantly rotating rapidly, as presently described. Said shaft 160 is automatically movable vertically so that when it 40 is raised to the position shown in Fig. 6, it transmits its own high speed of rotation to that one of the four shafts 92 which is then in alignment with it. This imparts a 45 somewhat planetary motion to the ironing block 95 owing to the eccentricity of stud 94 and causes the upper face of said block 95 to iron or polish the under face of the toplift which is then being held down by the 50 plunger 56.

We will now describe the means whereby the shaft 160 is elevated at the proper time to cause the clutch member 159 to engage clutch member 93. To this end, as shown 55 in Fig. 6 the shaft 160 is provided with a fixed collar 164 above which is a grooved collar 165 between which and the hub of the clutch member 159 is a compression spring 166. Blocks carried by the yoke 167 60 of a lever 168 fit the groove of the collar 165. The lever 168 is pivoted at 169 to a lug projecting from the bearing sleeve 22 and has a roll 170 adapted to be acted upon by a cam rise 171 formed or provided on 65 the upper margin of the pinion 32. A suit-

able spring 172 is provided to insure lowering of the outer end of lever 168 and the shaft 160 after cam 171 has passed the roll 170. The spring 166 is a cushion spring employed to yieldingly transmit the lift 70 imparted to collar 165 by lever 168 to the clutch member 159.

During the operation of the machine each toplift is subjected to pressure at stations B and C which, without unduly reducing its thickness, solidifies it. Also, its thickness is measured, and, owing to the lateral support provided by the wall of the opening in the mold plate and the vertical support entirely across the under surface of the blank, the edges of the blank are molded to proper shape. This occurs, as will be hereinafter explained, before the toplift is skived and reaches ironing station D. We will now describe the means whereby the measured thickness of each toplift is automatically stamped upon the toplift at station E, and the toplifts then distributed into different receptacles so that all of those of the same thickness will be deposited in one receptacle. The mechanism for doing this is best shown in Figs. 7 and 15, said mechanism being located at that portion of the machine so as to act upon toplifts when they reach station E. A wheel 173 having its periphery provided with proper dies is rotatably mounted in a bracket 174 depending from the plunger head 50 (Fig. 1) and the shaft of said stamping wheel has a pinion 175 engaged by a toothed segment 176 carried by a rock shaft 177 mounted in said bracket. A link 178 is connected at one end to the segment 176 and at the other end is pivotally connected at 179 to an angle lever 180 which is pivotally mounted at 181 and has a roll 182. Pivotally mounted adjacent the upper end of the central tube 29 of the turret are four strips 183, the outer end of each of said strips bearing upon the rounded upper end of a ratchet 108. These strips 183 will be referred to as guides because each of them acts, as the turret revolves, to guide the roll 182 on to the ratchet 108, the tip end of the guide simply resting between said ratchet and roll momentarily when the plunger head descends and the turret is stationary so that such downward movement of the turret head will act, through the roll 182 and the end of strip 183 to slightly swing the pivoted ratchet 108 which is then at station E, away from the position shown in Fig. 6, and cause the toothed portion of said ratchet to be temporarily in engagement with locking tooth 110 so that slide 97 can not be pushed down below the position at which it is then being held by tooth 101 and the teeth of detent 102.

Connected to the rock shaft 177 so as to 120

swing simultaneously with the toothed segment 176 is an arc shaped ratchet 184 (Figs. 7 and 15), the teeth of said ratchet being so formed that, when engaged by a toothed 5 arm 185, the stamping wheel 173 will be locked in the position to which it has been shifted by the descent of the plunger head through connections including ratchet 108, roll 182, lever 180 and link 178. When 10 the plunger head descends, the stamping wheel remains in rotative position to which it has been automatically adjusted so that the lowermost die carried by the wheel will impress the proper numeral or symbol 15 in the toplift. The toothed arm 185 referred to is to be later disengaged from the ratchet 184 so that the weight of lever 180 and its roll will swing the parts back to the normal position shown in Fig. 7. To effect 20 this separation of the toothed arm 185 from the ratchet, said arm, which is pivoted, is provided with another arm 186 the downwardly extending tip of which is laterally inclined as shown by comparing Figs. 25 3 and 7 so that, after the turret begins to rotate further, one side of the guide 183 which has been concerned in the previous operation will engage the inclined surface of arm 186 and raise said arm and lower 30 the toothed arm 185. This permits the return of the stamping wheel to normal position.

A bar 187 (Figs. 7 and 15) has a toothed 35 end forming a rack 188, said end of the bar riding on a roll 189 mounted in the bracket 174. The rack 188 is constantly in mesh with the pinion 175 and therefore when the stamping wheel is rotated first in one direction and then the other, said bar 187 is reciprocated to an extent determined by the 40 amount of movement imparted to the stamping wheel and said bar by the mechanism hereinafter described, effects distribution of the toplifts into different receptacles according to the thickness of said articles. Before 45 describing the mechanism operated by the reciprocations of the bar 187, we will describe how the mold plate is slid outwardly to the dotted line position shown in Fig. 7 when position E is reached so that the toplift can be removed from the opening in the 50 mold plate, said mold plate then remaining in that outward position until the turret is again actuated to carry said mold plate around to position B (Fig. 3) later to receive another toplift from the feed slide 113. To provide for outward movement of the 55 mold plate, said plate has a pair of hooks or lugs 190 at its outer end which are engaged by a pair of hooks 191 yieldingly connected 60 with the upper end of a forked lever 192 (see also Fig. 3). Said lever is pivoted at 193 to a bracket 194 of the frame base and has a short arm 195 connected by a link 196 65 (Fig. 2) with the upper arm of an elbow

lever 197, the lower arm of which has a roll 70 engaging a cam formed in the side of a disk 198 fixed to shaft 40. Said cam, like the other cams carried by shaft 40, is a quadruple acting cam because of the turret having four steps of rotation, as hereinbefore explained. As the turret revolves each mold plate moves so that its lugs 190 pass sideways onto the lever hooks 191 to position to be engaged by said hooks 191 when the cam 75 actuates the lever to slide the mold plate outward.

When the mold plate has been moved out, as described, the next operation is to remove the measured, skived, ironed and stamped toplift from the mold plate. The toplift is ejected from the opening in the mold plate by a plate 199 (Fig. 7) carried at the end of an angular arm having a toothed segment portion 200 and pivotally supported at 201 near the upper end of bracket 194 (Fig. 7). The segment 200 is in mesh with a segmental gear 202 pivotally supported at 203 and having a short arm to which is pivotally connected at 204 a link 205. The lower end of said link (Fig. 2) has a universal joint connection with a lever 206 which has a roll 80 engaged by a path cam in the side of disk 198 opposite from that side which appears in Fig. 2.

Supported by the upper end of a curved arm 207 of bracket 194 is an inclined stop plate 208 (Fig. 7) so located that a lift 85 which is ejected by plate 199 will not be thrown, by such movement, beyond a predetermined point. Practically the plate 208 acts also as a guide to insure that the ejected and lifted toplift will slide off from the ejector plate in a predetermined direction.

Extending down from opposite edges of the 90 plate 208 are two fingers 209 which are preferably laterally adjustable so as to effect a slight friction between them and the edges of the toplift as said toplift is moved upwardly from the full to the dotted line position indicated in Fig. 7, the object of said fingers 209 being to prevent the toplift from prematurely slipping off edgewise from the 95 ejector plate. The upper portions of the fingers 209 are far enough apart so as to retain no frictional hold of the toplift when it reaches position in contact with or adjacent to the plate 208, this shape of the plates being indicated in the plan view (Fig. 3).

If the toplift does not leave the ejector plate 100 when the latter is fully raised, because of any temporary clamping effect between the two plates 199, 208, it will do so as soon as the ejector plate 199 moves away and downwardly from plate 208. The toplift then 105 slides down over a chute plate 210 movably supported as presently described, said toplift sliding through a slot 211 formed for this purpose in the mold plate (Figs. 3 and 7).

The chute plate 210 guides the toplift into one of a series of receptacles 212 indicated by dotted lines in Fig. 1. In order that the toplift will be directed into the receptacle 5 or pocket for the lifts of a certain thickness, the plate 210 is pivotally supported at 201 and is swung to the proper degree of angularity by means of a curved arm 213 connected to said plate 210 and pivotally connected at 214 with the outer end of the bar 187. Since the bar 187 is moved endwise by the pinion 175 to a greater or lesser extent according to the size thickness of each toplift, the chute plate 210 will have its 15 degree of inclination varied properly so as to effect deposit of all toplifts of a given size thickness in a predetermined receptacle. In other words, the toplifts will be stacked in different receptacles according to their 20 thicknesses.

A spring 215 connected at one end to the arm 213 is provided to exert a slight tendency to hold said arm 213 normally in position determined by any suitable adjustable 25 stop.

As shown in Figs. 8 and 9 the plunger 56 which holds the toplift while it is being ironed, is vertically adjustable relatively to the plunger head 50. It may be yieldingly 30 mounted or not. As shown in each of said figures the stem 216 of the plunger 56 is mounted in a vertically adjustable bushing 217 fitting a screw-threaded aperture in the head 50, said stem having a head 218. In 35 Fig. 8 the spring 219 is illustrated, said spring being coiled around the stem 216 between an internal shoulder of the bushing and the top of the plunger 56. Normally the head 218 determines the lowermost position 40 of the stem and plunger relatively to the adjustable bushing 217, the spring 219 permitting the plunger to yield so that there will be no very great difference in the pressure exerted upon the toplift when the plunger 45 head 50 descends, if the toplift should be somewhat thicker than usual or thicker than the plate 127. This amount of yielding pressure may be determined by adjusting the bushing 217, the described adjustment being 50 rendered permanent by a lock nut 220.

In Fig. 9 the structure is substantially the same but in place of the spring 219 a rigid or unyielding bushing 221 is inserted thereby insuring downward movement of the plunger 56 to the same extent as the movement of the plunger head 50, regardless of thickness of the toplift. By simply substituting the rigid bushing 221 for the spring 219, or vice versa, the machine is adapted 60 to effect either a rigid or a yielding pressure on the toplift. While the interchangeable device illustrated in Figs. 8 and 9 is preferred for the plunger 56, which acts at the ironing station D, the same may be used 65 for the plungers 54, 55 at stations B and C.

As the lower portions of some lifts *a* will extend below the planes of the bottoms of the mold plates, the tops of the outer walls of the pockets 67 are notched or recessed at 222 (Figs. 6 and 7) to provide for the free 70 passage of said lower portions of the lifts when the mold plates carrying them move out at station E.

In operation, assuming that the hopper 111 contains a supply of toplift blanks of 75 miscellaneous thicknesses, the lowermost blank is first transferred by the feed slide 113 to station A under the plunger 143 which then acts to push the blank out of the opening 114 and into the opening 129 of 80 mold plate 127 imparting a preliminary pressure to, and partially compressing the blank while doing so, the two plates then occupying the relative positions shown in Fig. 12. This locates the blank in the opening 129 and upon the second or complete 85 inward movement of the slide 113 both plates move into the position shown in Fig. 13, this being station B. While the blank is at station A the downward movement of 90 the plunger 143 transmits motion (through the blank) to the support or table 131 (see left-hand portion of Fig. 6) and this downward movement, which imparts the preliminary pressure described to the blank, is 95 transmitted through the stem 132 to the lever 136, the spring 133 being compressed to some extent. The dog 138 of lever 136 becomes interlocked with the ratchet 139 at 100 the point to which the lever 136 has been depressed, and therefore the support 131 remains at its lower position until said dog 138 is later released or unlocked due to the action of the outwardly moving lever 116 upon the tripping lever 140.

The feed slide 113, during its two-step 105 inward movement, first receives a blank *a* from the hopper and carries it to station A for transfer to the mold plate and then acts to push the mold plate in to station B under plunger 54. The plunger head then descends by the operation of the mechanism hereinbefore described, and the lift *a* is forced more deeply into the opening in the mold plate 127 and is compressed between 110 plunger 54 and the block 95 against the expansive action of spring 71. The amount of downward movement of the block 95 is transmitted to lever 74 and the pawl 78 is automatically interlocked with the ratchet 80.

The turret then makes another step of rotation so that the lift *a* just mentioned is transferred to station C (see left-hand portion of Fig. 7) and then when the plunger head again acts plunger 55 imparts a second compression to the lift *a* the pawl 78 moving further down the ratchet 80. At the same time the pin 100 of the lever 74 acts through the link 99 to pull down the slide 97 and the tooth 101 is automatically interlocked with 115 120 125 130

the ratchet 102 therefore the block 95 and the slide 97 are locked in the position to which they have been depressed, the amount of depression depending upon the thickness 5 of lift a .

The result or effect of lowering the slide 97 as described, and locking it, is to indicate the thickness of the lift under pressure. The extent of depression of the slide controls 10 the extent of operation of the lever 180 which, in turn, actuates the marker 173 to proper position when that slide 97 reaches station E and the plunger head descends.

After the plunger head 50 rises and the 15 turret then makes another step of rotation carrying the particular toplift described around to station D, the upper flesh side of the lift a is skived by the knife 153. This skiving does not result in reducing all of 20 the lifts a acted upon by the machine to the same thickness because the upper surfaces of all lifts are forced downward to a predetermined plane according to the point or plane to which the plungers descend. The lower 25 surfaces of the lifts may occupy different planes when the lifts reach the knife, according to the different thicknesses of said lifts. Therefore, the skiving does not affect the actual accurate measuring of the lifts 30 which measuring has been preliminarily effected at station C, and which measuring is later recorded according to the height of slide 97 which remains constant until the ratchets and pawls are unlocked as herein- 35 after described.

As the turret moves toward ironing station D (see right hand portion of Fig. 6), the forked lever 168 is acted upon by the cam 171 which causes said lever to lift the 40 clutch member 159 into engagement with clutch member 93 so that the continuously rotating shaft 160 imparts rotary motion to the shaft 92 and the eccentric stud 94 of the latter imparts a revolving or somewhat 45 planetary movement to the block 95 whereby the upper surface of the latter irons the under surface of the lift a . This ironing effect of course is produced while the plunger head is down and the plunger 56 is holding the 50 measured and skived lift. During the next step of rotation of the turret to carry the lift from station D to station E, the roll 182 of lever 180 (see right hand portion of Fig. 55 7) rides up the inclined strip 183 thereby imparting as much motion to the lever 180 as will result from the degree of elevation of slide 97 which has been locked at a height co-ordinate with the thickness of the lift. Through the mechanism and connections 60 hereinbefore described, the marking or stamping wheel 173 is rotated to bring a symbol indicating the thickness of that lift down to such position that when the plunger head 50 next descends, the upper surface of 65 the lift will be marked by that particular

symbol. The point of rotation of the wheel 173 which has been so determined remains fixed while the plunger head again rises, due to the action of the ratchet 184 and toothed arm 185. After this the mechanism which 70 actuates the lever 192 causes the mold plate to move out to the dotted line position of Fig. 7, and after that the mechanism which lifts the ejector 199 acts to transfer the lift a to an elevated inclined position where it will 75 slide off and pass down the chute 210 into the particular receptacle which is to receive all of the lifts of that particular thickness.

During the next step of rotation of the turret during which the pocket or chamber 80 which has carried the toplift which has just been operated upon moves from station E to station B, the lever 192 swings back but the mold plate remains in its outer position so as to be in position to have its lift receiving 85 opening occupy station A (Fig. 3) ready to receive the next lift.

The purpose of the stationary cam ring 77 and the roll 76 carried by each of the levers 74 is to positively prevent any liability of 90 spring 71 causing a table 70 to be elevated to a plane too high for operation. That is, since the ring 77 prevents any lever 74 from being raised by a spring 71 above a predetermined limit, the uppermost position which 95 can be occupied by any blank supporting table is determined.

Preferably, although not necessarily, the 100 ring 77 has one portion of its lower surface a trifle lower than the rest of said surface, this portion being indicated in Fig. 6 so that when any blank supporting table reaches station B, the roll 76 of the lever which is connected to that particular table will ride on to a slightly lower portion of the ring 77 105 so as to render it certain that the table, and its ironing block 95, will be temporarily drawn down far enough so that there will be no liability of the edge of a toplift a which is pushed to position over the block 95 coming in contact with the edge of said block. That is, the upper surface of the block 95 is certain to be low enough so that no obstruction will be offered to the passage 110 of a top lift on to the upper surface of that block. 115

The purposes of the ratchet 108 at the top 120 of slide 97 is to prevent depression of the slide below the height to which it has been automatically set, by the pressure of the lever 180. When the plunger head descends roll 182 first acts through the tip of guide strip 183 (Fig. 7) to cause the ratchet 108 to swing enough to engage the fixed tooth 110 (Fig. 6) which then locks the slide against 125 depression and so enables the top of the slide to act as an abutment to cause lever 180 to swing, when the head 50 moves down, and effect adjustment of the marking wheel as hereinbefore described. 130

The release of the several pawl and ratchet mechanisms, to effect the automatic return of the necessary parts of each group to normal positions to be ready to receive and act 5 upon another toplift, is obtained as follows:

The timing of the operation is such that one of the triggers 89 (Fig. 7) acts on tripping lever 81 to unlock pawl 78 from ratchet 80 just after station C is reached but before 10 the plunger head has completed its descent to effect the second compression at said station C. This does not effect or permit release of ratchet lever 102 from locking tooth 101 and therefore the slide 97 does not rise. 15 When station D is reached another trigger 89 acts on tripping lever 84 to again unlock pawl 78 from ratchet 80 so that the full upward pressure of spring 71 may cause a yielding ironing action of block 95 on the 20 grain surface of the lift. At this time ratchet lever 102 is still locked by tooth 101, but the pin 100 of lever 74 has moved up in the slot of link 99.

After the operation at station E which 25 has been hereinbefore described, the lower end of ratchet lever 102 rides on to the end α of cam 106 (Fig. 5) so that said lever swings out and its toothed portion separates from tooth 101 and the spring 107 lifts slide 30 97 to normal position where it remains until the next operation carries that particular toplift carrier from station B to station C.

During the operation of the machine illustrated in the drawings, each toplift is subjected to three pressures successively applied. The first of these is at station A when the plunger 143 acts to transfer the lift from the slide 113 to a mold plate 127. The base of the plunger 143, in plan, is shaped like a 40 toplift and is slightly smaller than the opening 114 in slide 113. As best shown in Figure 16, which represents a longitudinal section through said slide and plate, the walls of the opening 114 in the slide 113 are beveled, said opening being smaller at the bottom than at the top. It is to be understood that in plan the opening has the shape of a toplift, the transverse edge at the left in said figure being straight. The opening 129 45 in plate 127 is similarly shaped in plan, but is smaller than opening 114 and its left hand edge which is to shape the breast edge of the lift is vertical while the other portions of the edge of said opening 129 are beveled to give the customary shape to the lift mold 50 ed therein. As the plunger 143 (station A) descends to a limit approximating that indicated by dotted lines in Fig. 16, a lift which is in the opening 114 is pushed 55 through the smaller lower part of said opening and is partially compressed laterally, and as it passes then into opening 129 it is still further compressed laterally. If the lift 60 is thicker than the slide 127, which is usually 65 the case, said lift is subjected to pressure be-

tween plunger 143 and the plate 134 on the support 131 (Fig. 6). This provides a preliminary pressure and molding operation before the operation at stations B and C, where the mechanisms are preferably such as 70 to effect greater pressure than at station A. As has been explained, each plunger 54, 44, 56 is adjustable relatively to the head 50. Therefore, since the head always descends to a given plane, the distances to which the toplift will be further pressed into its mold plate are controlled by the setting of the plungers 75 in the head.

The plungers, of course, are never so set as to push a toplift so far down that its upper surface will be below or flush with the upper surface of the mold plate. This is because the portion of the flesh side of each toplift which remains above the plane of the mold plate is the portion which is 80 skived off by the knife 153 while the toplift is passing from station C to station D. 85

The cumulative effect of the plurality of pressures successively applied at stations A, B and C is such as to avoid the disintegration of the fibers of the leather that would result if the total of those pressures were to be applied at one time. This applies especially to the treatments at stations B and C where the pressure effected is greater than 90 at station A. In another aspect the work is so divided that lateral compression of the leather due to the beveled sides of the mold openings 129 does not result in buckling or 95 wrinkling the leather. 100

It is to be understood that such terms as "compressing" and "compression," used herein, mean that when toplift blanks are operated upon they are subjected to such pressure as will be sufficient to effect the 105 measuring operation described, and incidentally increase the density of the leather, the pressure not being such as to effect any appreciable or substantial change in the characteristics or qualities of the leather. 110

Having described our invention, what we claim as new and desire to secure by Letters Patent of the United States is:

1. A machine of the character described, having, in combination, an intermittently movable carrier for a series of blanks, means for actuating said carrier to locate the blanks successively at different stations, and means for simultaneously compressing the blanks over their entire areas and measuring the thickness thereof. 115

2. A machine of the character described, having, in combination, an intermittently movable carrier for a series of blanks, means for actuating said carrier to locate the blanks successively at different stations, and means for simultaneously measuring and ironing a plurality of blanks occupying different stations. 120 123

3. A machine of the character described, 130

- having, in combination, an intermittently movable carrier for a series of blanks, means for actuating said carrier to locate the blanks successively at different stations, and means for simultaneously measuring, ironing and stamping a plurality of blanks occupying different stations. 1. A machine of the character described, having, in combination, an intermittently movable carrier for a series of blanks, means for actuating said carrier to locate the blanks successively at different stations, means for simultaneously compressing the blanks and measuring the thickness thereof, and means for skiving the blanks as they pass from one station to another. 2. A machine of the character described, having, in combination, a turret having a plurality of mechanisms for carrying a series of blanks, means for actuating said turret to locate the blanks successively at different stations, and means for simultaneously measuring, ironing, and stamping a plurality of blanks occupying different stations. 3. A machine of the character described, having, in combination, a plate having an opening for a blank, means for intermittently transporting said plate successively to different stations, and means for imparting a succession of cumulative pressures to the blank at said stations. 4. A machine of the character described, having, in combination, an intermittently rotatable turret having a series of mold plates, means for intermittently actuating the turret to cause each plate to successively occupy different stations, and means for imparting a succession of cumulative pressures to the blank at said stations. 5. A machine of the character described, having, in combination, an endless series of duplicate blank-supporting tables, means for holding a blank in position above each table, means for actuating said series of tables to cause each to successively occupy different stations, and means for compressing each blank and measuring its thickness by successive operations at different stations. 6. A machine of the character described, having, in combination, a mold plate, means for supplying a blank thereto, means for transferring said plate and blank successively to a plurality of stations, and means for operating on the blank while held by the mold plate, at the different stations, to compress it and measure its thickness. 7. A machine of the character described, having, in combination, a mold plate, means for supplying a blank thereto, means for transferring said plate and blank successively to a plurality of stations, and means for operating on the blank while held by the mold plate to compress it, measure its thickness and even its flesh surface. 8. A machine of the character described, having, in combination, an endless series of duplicate blank-supporting tables, means for holding a blank in position above each table, means for actuating said series of tables to cause each to successively occupy different stations, and means for compressing each blank and measuring its thickness by successive operations at different stations. 9. A machine of the character described, having, in combination, an endless series of duplicate blank supporting tables, means for holding a blank in position above each table, means for actuating said series of tables to cause each to successively occupy different stations, and means for imparting a succession of cumulative pressures to the blanks at different stations. 10. A machine of the character described, having, in combination, an endless series of duplicate blank-supporting tables, means for holding a blank in position above each table, means for actuating said series of tables to cause each to successively occupy different stations, and means for compressing each blank and measuring its thickness by successive operations at different stations. 11. A machine of the character described, having, in combination, an endless series of duplicate blank-supporting tables, means for holding a blank in position above each table, means for actuating said series of tables to cause each to successively occupy different stations, and means for compressing, measuring, and ironing the blanks at different stations. 12. A machine of the character described, having, in combination, an endless series of duplicate blank-supporting tables, means for holding a blank in position above each table, means for actuating said series of tables to cause each to successively occupy different stations, and means for compressing, measuring, and ironing the blanks and applying designations of thickness to said blanks at different stations. 13. A machine of the character described, having, in combination, a turret having a series of duplicate blank supporting tables, mold plates for holding blanks in position above said tables, means for actuating the turret to cause each of the tables to successively occupy different stations, and means for compressing the blanks and measuring their thickness by successive operations at different stations. 14. A machine of the character described, having, in combination, a mold plate, means for supplying a blank thereto, means for transferring said plate and blank successively to a plurality of stations, and means for operating on the blank while held by the mold plate, at the different stations, to compress it and measure its thickness. 15. A machine of the character described, having, in combination, a mold plate, means for supplying a blank thereto, means for transferring said plate and blank successively to a plurality of stations, and means for operating on the blank while held by the mold plate to compress it, measure its thickness and even its flesh surface. 16. A machine of the character described, having, in combination, a mold plate, means for supplying a blank thereto, means for transferring said plate and blank successively to a plurality of stations, and means for operating on the blank while held by the mold plate to compress it, measure its thickness, skive one side of it, and iron its other side. 17. A machine of the character described, having, in combination, a mold plate, means for supplying a blank thereto, means for transferring said plate and blank successively to a plurality of stations, and means for operating on the blank while held by the mold plate to compress it, measure its thickness, skive one side of it, iron its other side,

- and apply to it a designation of its thickness.
18. A machine of the character described, having, in combination, a mold plate, means for supplying a blank thereto, means for transferring said plate and blank successively to a plurality of stations, and means for operating on the blank while held by the mold plate, at the different stations, to compare 10 press it, measure its thickness, iron it, and apply to it a designation of its thickness, means being also provided to deliver the blanks from the machine and distribute them according to the thicknesses thereof.
19. A machine of the character described, having, in combination, two relatively movable members for subjecting a blank to pressure between them over its entire area, one of said members being yieldingly mounted 20 and the other being positively moved toward and from it, and means connected with said yielding member for indicating the thickness of the pressed blank.
20. A machine of the character described, having, in combination, a yielding member, an opposing member movable toward said yielding member to coact therewith to subject a blank to pressure between said members over its entire area, and means actuated 25 by movement of the yielding member for indicating the thickness of the blank.
21. A machine of the character described having, in combination, a yielding table, a movable presser for acting on a blank mounted 30 on said table, and means actuated by movement of the table for indicating the thickness of the blank acted upon by the presser and applying a thickness designation to the blank.
22. A machine of the character described having, in combination, a series of duplicate intermittently movable yielding tables, a presser for successively acting on blanks mounted on said tables, and means actuated 35 by the movement of each table for indicating the thickness of the blank acted upon by the operating presser.
23. A machine of the character described having, in combination, a resiliently-mounted table, means for locating a blank above the table, a plunger for compressing said blank between it and the table, and means controlled by movement of the table effected by the plunger pressure transmitted through 40 the blank for indicating the thickness of that blank.
24. A blank treating machine comprising, in combination, an intermittently rotatable turret having a plurality of duplicate resiliently-mounted tables and provided with means for locating a blank above each table, plungers for compressing blanks between them and the tables, and means controlled by movement of the tables for indicating 45 the thickness of the compressed blanks.
25. A blank treating machine comprising, in combination, a turret having four equidistant duplicate resilient blank supports, means for intermittently actuating the turret to locate the supports successively at each 50 of four stations, a head having three plungers opposite three of the supports, means controlled by movements of the blank supports at two of said stations to measure the thicknesses of the blanks, means for effecting 55 an ironing operation on each blank at the third station, and means at the fourth station for applying to each blank an indication of its thickness.
26. A blank treating machine comprising, in combination, a turret having four equidistant duplicate resilient blank supports, means for intermittently actuating the turret to locate the supports successively at each 60 of four stations, a head having three plungers opposite three of the supports, means controlled by movements of the blank supports at two of said stations to measure the thickness of the blanks, means for effecting 65 an ironing operation on each blank at the third station, means for skiving each blank as it approaches the third station, and means at the fourth station for applying to each blank an indication of its thickness.
27. In a blank treating machine, a turret having a plurality of duplicate mechanisms, each comprising a spring-supported table having a superimposed block, a mold plate above said block, a lever connected with the table, a measuring slide connected with the lever, and a clutch member connected with said block, means for actuating the turret to locate each of said mechanisms at a succession of stations, a head having a plurality 70 of plungers to operate at some of said stations, and means for engaging said clutch member at one of the stations to actuate the block to iron a blank in the mold plate associated with that block.
28. In a blank treating machine, a table having a spring for supporting it, means for adjusting said spring, a plunger for compressing a blank between it and said table, and means for imparting to said plunger a predetermined range of movement toward and from the table.
29. In a blank treating machine, a table having a spring for supporting it, means for adjusting said spring, a plunger for compressing a blank between it and said table, means for imparting to said plunger a predetermined range of movement toward and from the table, and means for adjusting the plunger to vary its limit of movement toward the table.
30. In a blank treating machine, a spring-supported table having an ironing member and a tubular stem, a shaft mounted in said stem and having a clutch member at one end and connected at its other end to the iron- 80

ing member to actuate it, a power-driven clutch driver normally disconnected from said clutch member, means for holding a blank firmly against the ironing member, and means for automatically inter-engaging the clutch driver with said clutch member for a predetermined length of time.

31. In a blank treating machine, a turret having a spring-supported table provided 10 with an ironing member and a tubular stem, a shaft mounted in said stem and connected to the ironing member to actuate it, means for intermittently rotating the turret to locate said table successively at different stations, means for holding a blank on the table, and means for rotating the shaft of the ironing member when the table reaches one of said stations.

32. In a blank treating machine, a turret 20 having a plurality of duplicate mechanisms, each including a spring-supported table provided with an ironing member and a tubular stem and a shaft mounted in the stem and connected to the ironing member, 25 means for intermittently rotating the turret to locate each of said mechanisms successively at different stations, means for supplying a blank to each of the tables when at one of said stations, and means for rotating each shaft of an ironing member 30 when at another of the stations.

33. A machine of the class described, having, in combination, an intermittently rotatable turret provided with a series of 35 blank supports, and means for performing a plurality of different operations upon blanks while held at different stations by the turret, said means including a head having a series of independently adjustable 40 plungers movable toward and from the turret.

34. In a blank treating machine, a spring-supported table, a plunger movable toward and from the table, a movable measuring 45 member connected with said table, and means for temporarily locking said member in the position to which it is shifted by movement of said table.

35. In a blank treating machine, a spring-supported table, a plunger movable toward and from the table, a movable measuring member, a lever connecting said table and measuring member, and ratchet mechanism for holding the lever in the position to which 55 it is shifted by movement of said table.

36. A machine of the class described, having, in combination, a spring-supported table, means for shifting said table from one station to another, a plunger for compressing a blank on the table when the latter is at one station, detent mechanism for temporarily retaining the table in the position to which it is moved by the action of the plunger, and means for releasing said 60 detent mechanism after the table passes

from the station at which the compression is effected.

37. A machine of the character described, having, in combination, a spring-supported table, means for shifting said table from 70 one station to another, a head having a plunger for compressing a blank on the table when the latter is at one station, detent mechanism for temporarily retaining the table in the position to which it is moved by the action of 75 the plunger, and means connected with said head for releasing the detent mechanism after the table passes from the station at which the compression is effected.

38. A machine of the character described, having, in combination, a spring-supported table, means for shifting said table from one station to another, a head having a plunger for compressing a blank on the 80 table when the latter is at one station, a lever connected with said table, ratchet mechanism connected with said lever for temporarily retaining the table in the position to which it is moved by the action of 85 the plunger, and means for releasing said detent mechanism after the table passes from the station at which the compression is effected.

39. A machine of the character described 95 having, in combination, a turret provided with a plurality of spring-supported tables and having a central tubular hub provided with openings, a vertically movable rod extending through said tubular hub and having a head provided with plungers for acting on blanks on said tables, detent mechanism for temporarily retaining each table in the position to which it is moved by the action of a plunger, triggers connected with 100 the vertically movable rod and adapted to be projected through the openings in the hub, and means actuated by said triggers for releasing the detent mechanism of each 105 table after such table passes from the station at which the compression is effected.

40. In a blank treating machine, a turret having a pocket, means for intermittently rotating the turret to transfer said pocket from one station to another, a spring-supported table in said pocket, a shaft extending through said table and having an eccentric stud at its upper end, a disk mounted on the table and having a recess engaged by said eccentric stud, means for holding a blank forcibly on said disk at one station to compress the blank, means for forcibly holding the blank on the disk at another station, and means for rotating said shaft when movement of the turret carries it to the last mentioned station.

41. A machine of the character described having, in combination, an intermittently movable turret provided with a series of 115 pockets, means for intermittently actuating 120

said turret to transfer each of said pockets successively from one station to another, a shaft in each pocket having an eccentric stud, a disk mounted on said stud, means for compressing a blank on each disk at one of said stations, and means located at another of said stations for rotating the shaft to cause the disk to iron a blank thereon.

42. A machine of the character described 10 having, in combination, co-operating flat blank compressing members engaging the entire area of the blank, a marker for applying to each compressed blank a designation of its thickness, an actuator for setting 15 the marker in appropriate marking position, and means connected with one of the compressing members for controlling the operations of said actuator.

43. A machine of the character described 20 having, in combination, a blank compressing plunger and a blank marker, a yieldingly mounted table for a blank, means for holding the table first at one station for action by the plunger and then at another station for action by the marker, an actuator for setting the marker in appropriate marking position, and means connected with said table for controlling the operation of said actuator.

30 44. A machine of the character described having, in combination, a blank compressing plunger and a blank marker, an intermittently rotatable turret having a plurality of yieldingly mounted tables, means 35 for actuating and holding the turret to present a blank on each table first at one station for the plunger and then at another station for action by the marker, an actuator for setting the marker in appropriate marking 40 position, and means connected with each of said tables for controlling the operation of said actuator.

45. A machine of the character described having, in combination, co-operating blank-compressing members, a marker for applying to each condensed blank a designation of its thickness, an actuator for setting the marker in appropriate marking position, a longitudinally movable slide for controlling the operation of the actuator, and means 50 connected with one of the compressing members for determining the longitudinal position of said slide.

46. A machine of the character described 55 having, in combination, co-operating flat blank-compressing members engaging the entire area of the blank, a marker for applying to each compressed blank a designation of its thickness, an actuator for setting the marker in appropriate marking position, a longitudinally movable slide for controlling the operation of said actuator, means connected with one of the compressing members for shifting said slide in one 60 direction, and ratchet detent mechanism for 65

holding the slide in the position to which it is moved by said compressing member.

47. A machine of the character described, 70 having in combination, a yieldingly supported table, a compressing member to coact with said table to compress a blank thereon, a marker for applying to each compressed blank a designation of its thickness, an actuator for setting the marker in appropriate marking position, a lever connected 75 with the table, and a slide operatively connected with said lever, said slide being constructed and arranged to control the operation of said actuator.

48. A machine of the character described, 80 having, in combination, a yieldingly supported table, a compressing member to coact with said table to compress a blank thereon, a marker for applying to each compressed blank a designation of its thickness, an actuator for setting the marker in appropriate marking position, 85 a lever connected with the table, a ratchet detent for holding the lever in the position to which it is shifted by movement 90 of the table, and a longitudinally movable slide connected with said lever to be actuated thereby, said slide being constructed and arranged to control the operation of the actuator for the marker. 95

49. A machine of the character described, having, in combination, co-operating blank-compressing members, a marker for applying to each compressed blank a designation of its thickness, an actuator for setting the marker in appropriate marking position, a longitudinally movable slide for controlling the operation of said actuator, a lever connected with one of said blank-compressing members and having a slot and pin connection with the slide, ratchet mechanism for holding the lever in the position to which it is moved by said compressing member, and independent ratchet mechanism for temporarily locking the slide. 100

50. A machine of the character described, 105 having, in combination, co-operating blank-compressing members, a marker for applying to each compressed blank a designation of its thickness, an actuator for setting the marker in appropriate marking position, a longitudinally movable slide for controlling the operation of said actuator, a lever connected with one of said blank-compressing members and having a slot and pin connection with the slide, ratchet mechanism for holding the lever in the position to which it is moved by said compressing member, a tooth carried by said slide, a pivoted ratchet for engaging said tooth, and means for automatically controlling the position of the pivoted ratchet. 115

51. A machine of the character described 120 having, in combination, co-operating blank-compressing members, a marker for apply- 130

- ing to each compressed blank a designation of its thickness, an actuator for setting the marker in appropriate marking position, a longitudinally movable slide for controlling 5 the operation of said actuator, a lever connected with one of said blank-compressing members, and having a slot and pin connection with the slide, ratchet mechanism for holding the lever in the position to which it 10 is moved by said compressing member, a tooth carried by said slide, a pivoted ratchet for engaging said tooth, and cam mechanism for automatically controlling the position of the pivoted ratchet.
- 15 52. A machine of the character described, having, in combination, a yieldingly supported table, a compressing member to coact with said table to compress a blank thereon, a marker for applying to each compressed 20 blank a designation of its thickness, an actuator for setting the marker in appropriate marking position, a lever connected with the table, a ratchet detent for holding the lever in the position to which it is shifted by 25 movement of the table, a longitudinally movable slide connected with said lever and having a pivoted ratchet member formed to engage the marker actuator, and a locking tooth for said pivoted ratchet.
- 30 53. A machine of the character described having, in combination, a carrier provided with a plurality of molds, means for actuating the carrier to locate the molds successively at different stations, a hopper for 35 blanks, means for transferring a blank from the hopper to each mold as it arrives at the blank-receiving station, and means for simultaneously compressing and marking different blanks at other stations.
- 40 54. A machine of the character described having, in combination, a rotatable turret provided with a plurality of mold plates each having a blank-receiving opening, said plates being movable toward and from the 45 axis of rotation of the turret, means for supplying a blank to each mold plate while in its outer position, and means for performing a succession of operations on the blank after the mold plate carrying it is 50 shifted to its inner position.
- 55 55. A machine of the character described having, in combination, a rotatable turret, a plurality of mold plates mounted thereon, means for intermittently rotating the turret 55 to temporarily locate each mold plate successively at different stations, means for automatically shifting said plates radially relatively to the axis of rotation of the turret, means for supplying a blank to each 60 mold plate while in its outer position, and means for performing a succession of operations on each blank after the mold plate carrying it is shifted to its inner position.
- 65 56. A machine of the character described having, in combination, an intermittently 70 rotatable table provided with a plurality of radial ways, mold plates mounted in said ways, means for automatically shifting each mold plate outwardly at one station and inwardly at another station, means for supplying a blank to each mold plate while in its outer position, and means for performing a succession of operations on the blank after the mold plate carrying it is shifted to its inner position.
- 75 57. A machine of the character described having, in combination, an intermittently rotatable turret provided with a plurality of movable blank molds, blank compressing devices outside of the turret, and means for moving each blank mold to cause it to temporarily occupy a position in operative relationship with said compressing devices.
- 80 58. A machine of the character described having, in combination, an intermittently rotatable turret provided with a plurality of chambers, spring-supported tables in said chambers, blank molds mounted on the table and movable to and from position over said chambers, and means for simultaneously 85 performing different operations upon blanks carried by said molds.
- 85 59. A machine of the character described having, in combination, an intermittently 90 rotatable turret provided with a plurality of blank molds, a blank-supply hopper at one side of the turret, a slide for feeding blanks from the hopper to the turret molds, and means for imparting compressing pressure to a blank while carried by said slide.
- 95 60. A machine of the character described having, in combination, an intermittently 95 rotatable turret provided with a plurality of blank molds, a blank-supply hopper at one side of the turret, a chamber having a spring-supported table between the turret and hopper, a plunger above said table to co-operate therewith, a slide for feeding blanks from the hopper to the turret molds, and means for actuating said plunger to transfer a blank from the slide to a mold and impart preliminary pressure thereto.
- 100 61. A machine of the character described having, in combination, an intermittently 100 rotatable turret provided with a plurality of blank molds, a blank-supply hopper at one side of the turret, a chamber having a spring-supported table between the turret and the hopper, said table having a stem, a lever connected with said stem, means for automatically locking said lever when it is depressed, a plunger above said table to co-operate therewith, a slide for feeding blanks from the hopper to the turret molds, and means for actuating said plunger to transfer a blank from the slide to a mold and impart preliminary pressure thereto.
- 105 62. A machine of the character described having, in combination, an intermittently 105

- rotatable turret provided with a plurality of radially movable molds, means for projecting each mold to blank-receiving position, a blank-supply hopper at one side of the turret, a slide for feeding blanks from the hopper to the molds, and means between the turret and hopper for transferring a blank from the slide to a mold and imparting preliminary pressure thereto. 5
63. A machine of the character described having, in combination, an intermittently rotatable turret provided with a plurality of radially movable molds, means for projecting each mold to blank-receiving position, a blank-supply hopper at one side of the turret, a slide for feeding blanks from the hopper to the molds, means carried by said slide to engage a projected mold to push it in, means between the turret and hopper for transferring a blank from the slide to a mold, and means for imparting a two step movement to said slide to first locate a blank in position for transfer to the mold and to then push the mold to inner position on the turret. 10
64. A machine of the character described having, in combination, a mold carrying turret, a blank-supply hopper at one side of the turret, a chamber between the turret and the hopper, a spring-supported table mounted in said chamber and having a changeable top plate, a feed slide movable from the hopper over said table to position for transfer of a blank from the slide to a mold, and a plunger for pressing a blank carried by the slide into said mold while the latter is in position above said table. 15
65. A machine of the character described, having, in combination, a turret having a plurality of molds, a blank-supply hopper at one side of the turret, a yieldingly mounted table between the hopper and turret, a blank feeding slide movable over the table, means for compressing a blank on said table, means for locking the table when depressed, a lever for actuating the slide, and means operatively connected with the lever for unlocking the table when the lever and slide move to normal position. 20
66. A machine of the character described having, in combination, a turret having a plurality of molds, a blank-supply hopper at one side of the turret, a yieldingly mounted table between the hopper and turret, a blank feeding slide movable over the table, means for compressing a blank on said table, a ratchet mechanism for locking the table when depressed, a lever for actuating the slide, a pivoted ratchet-releasing device, and means carried by said lever for actuating the ratchet-release device when the lever and slide move to normal position. 25
67. A machine of the character described having, in combination, an intermittently rotatable turret and means co-operating therewith to compress blanks carried thereby, a blank feeder having means for moving it toward and from the turret, means for supplying a blank to the feeder at one point of its range of movement, and means for applying compressing pressure to the blank while held by the feeder at another point of its range of movement. 30
68. A machine of the character described having, in combination, an intermittently rotatable turret and means co-operating therewith to compress blanks carried thereby, a feed slide movable toward and from the turret, means for supplying a blank to the slide at one point of its range of movement, and means for applying compressing pressure to the blank while held by the slide at another point of its range of movement. 35
69. A machine of the character described having, in combination, an intermittently rotatable turret having a plurality of molds, means co-operating with the turret and molds to compress blanks carried by the molds, a feed slide movable toward and from the turret, means for supplying a blank to the slide at one point of its range of movement, and means for applying compressing pressure to the blank while held by the slide at another point of its range of movement. 40
70. A machine of the character described having, in combination, an intermittently rotatable turret having a plurality of molds, means co-operating with the turret and molds to condense blanks carried by the molds, a feed slide movable toward and from the turret, means for supplying a blank to the slide at one point of its range of movement, and means for simultaneously transferring a blank to a mold and applying compressing pressure to said blank while said slide is at another point of its range of movement. 45
71. A machine of the character described having, in combination, an intermittently rotatable turret having a plurality of molds, means co-operating with the turret and molds to compress blanks carried by the molds, a feed slide movable toward and from the turret, means for supplying a blank to the slide at one point of its range of movement, and a plunger and a co-operating yielding support constructed and arranged for simultaneously transferring a blank to a mold and applying compressing pressure to said blank while the slide is at another point of its range of movement. 50
72. A machine of the character described having, in combination, a blank mold, means for compressing a leather blank therein to a point to leave the flesh surface of the blank projecting a predetermined amount from the mold, and means for reducing said flesh surface evenly to a plane determined by the plane of the mold. 55
73. A machine of the character described having, in combination, an intermittently 120

having, in combination, a laterally movable blank mold, means for compressing a leather blank therein to a point to leave the flesh surface of the blank projecting a predetermined amount from the mold, and means for reducing said flesh surface evenly to a plane determined by the plane of the mold.

74. A machine of the character described having, in combination, a laterally movable blank mold, means for compressing a leather blank in said mold to a point to leave the flesh surface of the blank projecting a predetermined amount from the mold, and means for acting upon the blank while the mold is moving laterally to evenly reduce said flesh surface to a plane determined by the plane of the mold.

75. A machine of the character described having, in combination, a turret provided with a plurality of molds, means for intermittently rotating said turret to cause said molds to move laterally, means for successively compressing leather blanks in the molds to a point to leave the flesh surfaces of the blanks projecting a predetermined amount from the molds, and means for reducing the flesh surfaces of the blanks evenly to a plane determined by the plane of movement of the molds.

76. A machine of the character described having, in combination, a laterally movable blank mold, means for compressing a leather blank therein to a point to leave the flesh surface of the blank projecting a predetermined amount from the mold, and a stationary knife for skiving said flesh surface in a plane determined by the plane of the mold.

77. A machine of the character described having, in combination, a laterally movable blank mold, means for compressing a leather blank therein to a point to leave the flesh surface of the blank projecting a predetermined amount from the mold, a stationary knife for skiving said flesh surface evenly, and means for adjusting the knife relatively to the plane of movement of the mold.

78. In a blank treating machine, an intermittently rotatable blank-carrying turret having a normally idle vertical shaft provided with a polishing iron at its upper end, a driver for said shaft normally disengaged therefrom, and means for automatically interengaging said driver and shaft at a predetermined point of rotation of the turret.

79. In a blank treating machine, an intermittently rotatable turret having a plurality of normally idle vertical shafts provided with polishing irons at their upper ends, means for holding a blank firmly on each iron when the latter is at one of the stations of turret movements, a driver for said shaft located at said station, and means for interengaging the driver with the shaft then in position to be driven.

80. In a blank treating machine, an intermittently rotatable turret having a plurality of normally idle vertical shafts provided with polishing irons at their upper ends, means for holding a blank firmly on each iron when the latter is at one of the stations of turret movements, clutch members at the lower ends of said shafts, a continuously operating shaft located at said station and having a clutch member at its upper end, and means for controlling the position of the continuously operating shaft to transmit motion to the turret shaft which is then in position to be driven.

81. In a blank treating machine, an intermittently rotatable turret having a plurality of normally idle vertical shafts provided with polishing irons at their upper ends, means for holding a blank firmly on each iron when the latter is at one of the stations of turret movements, clutch members at the lower ends of said shafts, a continuously operating shaft located at said station and having a clutch member at its upper end, and means for controlling the position of the continuously operating shaft to transmit motion to the turret shaft which is then in position to be driven, said controlling means comprising a lever operatively connected with the continuously operating shaft and a cam for actuating said lever.

82. A machine of the character described having, in combination, an intermittently movable blank carrier, means for actuating said carrier to locate a blank successively at different stations, means for measuring the thickness of the blank while it is stationary at one station, a marking wheel and means for effecting contact thereof with said blank while it is stationary at another station, and means controlled by the thickness of that blank for varying the rotary position of the marking wheel.

83. A machine of the character described having, in combination, an intermittently rotatable turret provided with a plurality of blank molds, means for measuring the thickness of blanks in said molds, a marking wheel movable toward and from the plane of movement of the molds, means for effecting contact of the wheel with each blank at a predetermined station of the turret, and means controlled by the thickness of that blank for varying the rotary position of the marking wheel.

84. A machine of the character described having, in combination, an intermittently movable blank carrier, means for actuating said carrier to locate a blank successively at different stations, means for measuring the thickness of the blank at one station, a marking wheel and means for effecting contact thereof with said blank at another station, means for locking the marking wheel in the position to which it is adjusted according

to the thickness of the blank, and means controlled by the thickness of that blank for varying the rotary position of the marking wheel.

- 5 85. A machine of the character described having, in combination, an intermittently movable blank carrier, means for actuating said carrier to locate a blank successively at different stations, means for measuring 10 the thickness of the blank at one station, a marking wheel and means for effecting contact thereof with said blank at another station, means for locking the marking wheel when it contacts with the blank, means for 15 unlocking the wheel after it has marked a blank, and means controlled by the thickness of that blank for varying the rotary position of the marking wheel.

86. A machine of the character described 20 having, in combination, an intermittently rotatable turret provided with a plurality of blank molds, means for actuating said turret to locate each blank mold successively at different stations, a head having 25 a plunger for compressing a blank at one station, and means carried by said head at another station for applying to each blank a designation of its thickness.

87. A machine of the character described 30 having, in combination, an intermittently movable blank carrier, means for actuating said carrier to locate a blank successively at different stations, a head having a blank-marking wheel at another station, means 35 for moving said head toward and from the blank carrier, an adjustable member carried by said blank carrier, means for setting said member in a position determined by the thickness of the blank in the carrier, and 40 means for rotating the marking wheel according to the position of said adjustable member.

88. A machine of the character described 45 having, in combination, an intermittently movable blank carrier, means for actuating said carrier to locate a blank successively at different stations, a head having means for depressing the blank at one station, a blank-marker carried by the head at another station, an adjustable member carried by said blank carrier, means for setting said member in a position determined by the thickness of the depressed blank, and means for positioning the marker according 55 to the position of said adjustable member.

89. Means for marking blanks with indications of the thickness thereof, comprising a blank carrier having an adjustable member and means for setting said member 60 in a position determined by the thickness of a blank in the carrier, a marking wheel support movable toward and from the blank carrier, a marking wheel mounted in said support, and means actuated by movement 65 of the wheel support toward the blank car-

rier to rotate the wheel to a degree determined by the position of said adjustable member.

90. Means for marking blanks with indications of the thickness thereof, comprising 70 a blank carrier having an adjustable member and means for setting said member in a position determined by the thickness of a blank in the carrier, a marking wheel support movable toward and from the blank carrier, a marking wheel having a pinion mounted in said support, a toothed segment meshing with said pinion, and means actuated by movement of the wheel support toward the blank carrier to move 75 said segment and marking wheel to a degree determined by the position of said adjustable member.

91. Means for marking blanks with indications of the thickness thereof, comprising 80 a blank carrier having an adjustable member and means for setting said member in a position determined by the thickness of a blank in the carrier, a marking wheel support movable toward and from the blank carrier, a marking wheel having a pinion mounted in said support, a toothed segment 85 engaging said pinion, a lever carried by said support and having a link connecting it with said segment, and means actuated by movement of said support toward the blank carrier to oscillate said lever to a degree determined by the position of said adjustable member.

92. A machine of the character described 90 having, in combination, an intermittently rotatable turret provided with a plurality of radially movable molds, means for projecting the molds from the turret at one station, means for supplying a blank to each mold and retracting it at another station, means for performing a succession of operations on the blanks at intermediate stations, and means for ejecting the blanks from the molds at the first-mentioned station.

93. A machine of the character described 100 having, in combination, an intermittently rotatable turret provided with a plurality of radially movable molds, means for projecting the molds from the turret at one station, means for supplying a blank to each mold and retracting it at another station, means for compressing the blanks at an intermediate station, and means for 105 ejecting the blanks from the molds at the first-mentioned station.

94. A machine of the character described 110 having, in combination, an intermittently rotatable turret provided with a plurality of radially movable molds, means for projecting the molds from the turret at one station, means for supplying a blank to each mold and retracting it at another station, means for compressing and measuring the 115

blanks at intermediate stations, and means for ejecting the blanks from the molds at the first-mentioned station.

95. A machine of the character described
6 having, in combination, an intermittently rotatable turret provided with a plurality of radially movable molds, means for protecting the molds from the turret at one station, means for supplying a blank to 10 each mold and retracting it at another station, means for compressing and measuring the blanks at intermediate stations, means for skiving the blanks, and means for ejecting the blanks from the molds at the first-mentioned station.

96. A machine of the character described
having, in combination, an intermittently rotatable turret provided with a plurality of radially movable molds, means for projecting 20 the molds from the turret at one station, means for supplying a blank to each mold and retracting it at another station, means for compressing and measuring and skiving the blanks in the molds while the molds are 25 in retracted positions in the turret, and means for marking the blanks and ejecting them from the molds at the first-mentioned station of the turret.

97. A machine of the character described
30 having, in combination, an intermittently rotatable turret provided with a plurality of blank molds, means for measuring the thickness of blanks in said molds, a marking wheel movable toward and from the plane of movement of the molds, means for effecting contact of the wheel with each blank at a predetermined station of the turret, means controlled by the thickness of that blank for varying the rotary position of the marking 35 wheel, and means controlled by the rotary position of the marking wheel for delivering the blanks graded as to thickness.

98. A machine of the character described
40 having, in combination, a mold, means for operating on a blank in said mold, a movable blank distributor, an ejector for removing the blank from the mold and delivering it to the distributor, and means for adjusting the distributor according to the thickness 45 of said blank prior to the delivery of the blank to it.

99. A machine of the character described
50 having, in combination, a mold, an automatically adjustable marking wheel for applying to a blank in the mold a designation of its thickness, a movable blank distributor, an ejector for removing the blank from the mold and delivering it to the distributor, and means connected with the marking wheel for 55 adjusting the distributor.

100. A machine of the character described
60 having, in combination, a mold, an automatically adjustable marking wheel for applying to a blank in the mold a designation 65 of its thickness, a pivoted plate, an ejector

for removing the blank from the mold and delivering it to said plate, and means connected with the marking wheel for swinging said plate on its pivot.

101. A machine of the character described
70 having, in combination, an intermittently rotatable turret, a plurality of mold plates mounted to slide radially thereon, means for compressing blanks in the molds, means for partially withdrawing each mold plate 75 from the turret at a predetermined point of rotation of the latter, and means for removing the blank from the mold while so withdrawn.

102. In a machine of the character described, an intermittently rotatable turret provided with a plurality of radially movable plates having blank-molding openings, means for operating on blanks in said openings, means for partially withdrawing each 80 plate from the turret at a predetermined point of rotation of the latter, and an ejector movable through the opening of the withdrawn plate.

103. In a machine of the character described, an intermittently rotatable turret provided with a plurality of radially movable plates having blank-molding openings, means for operating on blanks in said openings, means for partially withdrawing each 85 plate from the turret at a predetermined point of rotation of the latter, an ejector movable upwardly through the opening of the withdrawn plate, and a stop to prevent the ejected blank from being thrown beyond a 90 predetermined point.

104. In a machine of the character described, an intermittently rotatable turret provided with a plurality of radially movable plates having blank-molding openings, means for operating on blanks in said openings, means for partially withdrawing each plate from the turret at a predetermined point of rotation of the latter, a pivotally mounted ejector movable through the opening of the withdrawn plate, an inclined stop to prevent the ejected blank from being thrown beyond a predetermined point, and means for frictionally engaging edge portions of the upwardly moving blank.

105. In a machine of the character described, an intermittently rotatable turret provided with a plurality of radially movable plates having blank-molding openings, means for operating on blanks in said openings, means for partially withdrawing each plate from the turret at a predetermined point of rotation of the latter, a pivotally mounted ejector movable upwardly through the opening of the withdrawn plate, an inclined stop plate mounted at a fixed point above the ejector and yielding friction fingers supported by said stop plate and extending down toward the plane of movement of the mold plate, said fingers being spaced.

to frictionally engage the edges of an upwardly moving blank.

106. In a machine of the character described, an intermittently rotatable turret provided with a plurality of radially movable plates having blank-molding openings, means for operating on blanks in said openings, means for partially withdrawing each plate from the turret at a predetermined point of rotation of the latter, an ejector

movable upwardly through the opening of the withdrawn plate, means for determining the point to which a blank can be shifted by said ejector, and an inclined plate for suitably directing each blank elevated by the 15 ejector.

In testimony whereof we have signed our names to this specification.

RALPH S. MEGATHLIN.
